UNITED STATES PATENT OFFICE.

WILLIAM E. CHIPMAN, OF EASTON, PENNSYLVANIA.

DESIGN FOR A STOCKING.

53,435.

Specification for Design. Patented June 17, 1919.

Application filed July 22, 1915. Serial No. 41,404. Term of patent 14 years.

To all whom it may concern:

Be it known that I, WILLIAM E. CHIPMAN, a citizen of the United States, residing at Easton, in the county of Northampton and State of Pennsylvania, have invented a new, original, and ornamental Design for Stockings, of which the following is a specification, reference being had to the accompanying drawing, forming part thereof.

Figure I, is a side view of a stocking showing my new design.

Copies of this patent may be obtained for five cents each, by addressing the "Commissioner of Patents, Washington, D. C."

Fig. II, is an enlarged view of a portion of the knit web corresponding to the indented band of contrasting color illustrating the scheme of knitting by which the effect is produced.

I claim:

The ornamental design for a stocking as shown.

WILLIAM E. CHIPMAN.
